BALL POINT WRITING INSTRUMENT

Herman C. Frentzel, Milwaukee, Wis., assignor
to The Parker Pen Company, Janesville, Wis.,
a corporation of Wisconsin

Application November 17, 1945, Serial No. 629,284

8 Claims. (Cl. 120—42.03)

1

This invention relates to ball-point writing instruments, and it has to do particularly with so-called duo-push type of project-retract mechanism therefor.

The primary object is to provide an improved writing instrument of the above-indicated character wherein consecutive depressions of the pushbutton are effective, alternately, to project and retract the writing point out of and back into the barrel of the instrument.

Another object is to provide a writing instrument of the ball-point variety whereof the component parts can be manufactured economically, requiring no excessively close tolerances.

Still another object is to provide a ball-point writing instrument of the two-push retractable point type which is easy to assemble and to disassemble when parts replacements are necessary.

A further object is to provide a ball-point writing instrument of the pushbutton operated project-retract type, the operativeness of which is not likely to become impaired as a result of wear occurring within the reasonable life expectancy of the instrument.

An additional object is to provide a ball-point writing instrument of the pushbutton operated project-retract type comprising a readily replaceable self-contained ball-and-cartridge unit.

A preferred embodiment of my invention is illustrated in the accompanying drawing, wherein:

Fig. 1 is a longitudinal sectional view of a ball-point writing instrument—the ball point being shown in retracted position;

Fig. 2 is an enlarged reproduction of a portion of Fig. 1, but slightly modified in order to show how the flexible plunger engages the latch member and is flexed thereby in a manner appropriate to move the latch member into latching position upon being propelled forwardly;

Fig. 3 is an enlarged fragmentary sectional view taken along line 3—3 of Fig. 1;

Fig. 4 is a longitudinal sectional view similar to Fig. 1 but showing the ball-and-cartridge unit in writing position;

Fig. 5 is an enlarged fragmentary view showing the flexible rod about to release the latch member for the purpose of retracting the ball-and-cartridge unit;

Fig. 6 is a transverse sectional view taken along line 6—6 of Fig. 4;

Fig. 7 is a transverse sectional view taken along line 7—7 of Fig. 1; and

Fig. 8 is an enlarged, separated, fragmentary, perspective view of the ball-and-cartridge unit and the latch member associated therewith.

2

The assemblage illustrated comprises an elongate tubular barrel 1 in which is housed a ball-and-cartridge unit 2 comprising a tubular ink reservoir 3 to which is connected an ink feed tube 4 having at its front end a writing ball 5. Within the ink reservoir is shown a metal ball 6 which serves as a seal and also as a weight for pressing the ink forwardly toward the writing ball. The rear end of the ink reservoir is closed by a plug 7 having a small axial aperture 8 through which air is admitted to the reservoir to prevent formation of a vacuum therein.

The ball-and-cartridge unit is reciprocable lengthwise in the barrel and is continuously urged rearwardly by a coil spring 9.

Threaded into the rear end of the barrel and forming a liner therein is a tubular sleeve 10 which is threaded internally to receive a screw bushing 11 which acts as a retainer and limiting means for a pushbutton member 12 which is reciprocable lengthwise in the bore of liner 10.

Liner 10 has an internal, annular bead 10^a which functions as a stop for a spring seat and centering member 13 serving as an abutment for a coil spring 14, the purpose of which is to retract pushbutton member 12 independently of spring 9.

Securely anchored in pushbutton member 12 and extending axially of the barrel is an elongate, flexible rod 15 on which is rigidly mounted a conical member 16 which normally seats in the bore of member 13 and serves to hold rod 15 centered when in its retracted position, as depicted in Fig. 1. Rod 15 is reciprocable axially with pushbutton member 12.

Pivottally connected to reservoir 3 by means of a pin 17 is a latch member 18 which is made from a piece of round stock and milled to form two flat parallel sides 18^a and 18^b, as shown most clearly in Fig. 7. The latch member 18 is inserted between two ears 3^a formed by slotting the end of the reservoir 3. The diameter of the stock from which member 18 is made is such that said member will fit freely in the bore of sleeve 10, as shown in Figs. 1 and 2. The inner portion is chamfered as indicated at 30 (Figs. 2, 5, 6 and 8).

Interposed between plug 7 and the front face of latch member 18 is a U-shaped spring 19 which continuously tends to rotate latch member 18 in a clockwise direction, as viewed in Fig. 1. Spring 19 has a small aperture 19^a in registration with aperture 8 so that said spring will not block admission of air to the ink reservoir.

The rear face of latch member 18 is formed as shown to present an apex 20 formed by two oppositely sloping surfaces 21 and 22 which terminate respectively in angularly extending surfaces

23 and 24, which constitute shoulders against which the free end of rod 15 is adapted to abut.

The apex 20 is so positioned on latch member 18 that when said latch member is disposed within the bore of liner 10, as depicted in Figs. 1 and 2, said apex is laterally offset in one direction with respect to the longitudinal axis of rod 15 so that when rod 15 is moved forwardly its free end will engage surface 22 and said rod will be flexed by the camming action of said surface into engagement with shoulder 24, as clearly shown in Fig. 2. Continued forward movement of rod 15, caused by depressing pushbutton 12, will result in a forward movement of latch member 18 which, in turn, causes a forward movement of the ball-and-cartridge unit. Pin 17 is so positioned laterally with respect to the point of contact of rod 15 with latch member 18, as depicted in Fig. 2, that upon movement of said latch member forwardly to a point where it is clear of the forward end of liner 10, and release of the push button 12, the latch member is toggled into the position in which it is shown in Fig. 5, wherein one edge of the latch member is engaged by the forward edge of said liner in such manner as to latch the ball-and-cartridge unit in its forward position. When the pushbutton is released, said pushbutton, together with rod 15, is retracted by spring 14, as illustrated in Fig. 4, but the ball-and-cartridge unit remains latched in its forward position.

With latch member 18 in its latched position, as depicted in Figs. 4 and 5, the apex 20 is laterally displaced from the longitudinal axis of flexible rod 15 in a direction opposite to the lateral displacement depicted in Fig. 2. If, thereafter, pushbutton 12 is again depressed, the free end of said rod will engage sloping surface 21 and will be cammed thereby into engagement with shoulder 23 and, in response to further forward movement of said rod, the latch member will be moved forwardly to some extent and at the same time rotated counterclockwise, as viewed in Fig. 5, so that upon a succeeding rearward movement it will enter the bore of liner 10 and thus reoccupy the position in which it is shown in Figs. 1 and 2.

A pocket clip 25 of conventional design may be provided.

It will be apparent that the objects of my invention have been achieved in that I have provided a pushbutton operated ball-point pen wherein consecutive operations of the pushbutton cause the writing point to be alternately propelled and retracted and wherein all of the parts are of simple design and capable of economical manufacture and easy assemblage. Also, it will be evident from inspection of the drawing that all of the component parts are easily replaceable, including the ball-and-cartridge unit.

My invention is clearly susceptible of various modifications and alternative embodiments and for that reason I do not wish to be limited except by the scope of the appended claims.

I claim:

1. In a ball-point writing instrument, a barrel having an opening at its front end, a ball-and-cartridge unit disposed within said barrel and reciprocable lengthwise thereof, said unit comprising an ink reservoir and a ball point connected to the front end thereof, a spring continuously urging said unit rearwardly, a pushbutton projecting rearwardly from the back end of said barrel and reciprocable lengthwise thereof, a laterally deflectable plunger rod anchored to said pushbutton and projecting forwardly therefrom

axially of the barrel, a spring continuously urging said pushbutton and plunger rod rearwardly, a latch member interposed between said unit and plunger rod and reciprocable bodily lengthwise of the barrel, said latch member being pivoted to oscillate rotationally between two limiting postures in a plane parallel to the horizontal axis of said barrel, means within said barrel defining a stationary shoulder with which said latch member is engageable, when in one of said limiting postures, to releasably hold said unit in its forward position, spring means biasing said latch member toward latching engagement with said shoulder, said latch member extending backwardly from its pivotal center toward said plunger rod and formed with two oppositely inclined surfaces which lie individually and alternately in the path of said plunger rod when said latch member is in either of the two aforementioned limiting postures respectively, whereby said plunger rod engages and shifts said latch member from whichever limiting posture it happens to occupy to the alternate limiting posture thereof and retains the latch member in said alternate limiting posture during the succeeding rearward movement of the unit and plunger rod.

2. A ball-point fountain pen comprising a barrel, a ball point supporting means reciprocably mounted therein and having a ball writing point in its forward end, and propelling and retracting means for projecting said point from and alternately retracting it into said barrel, said means comprising spring means constantly urging said supporting means in retracting direction into the barrel, stop means in said barrel, a latch member pivotally associated with the rear end of said supporting means, spring means normally urging said latch member rotatably in one direction to engage said stop means, and a push member reciprocably mounted in said barrel in position to engage said latch member when the latter is disengaged from said stop means and propel said latch member and said supporting means forwardly to a position wherein said writing point is projected out of said barrel and said latch member is rotated by said spring to engage said stop means and to hold the part so propelled, said latch member having a shoulder offset laterally of its pivotal support away from said stop means with a cam surface leading thereto, said cam surface being aligned with said push member when said latch member is engaged with said stop means so that said push member upon reciprocation is guided by said cam surface to engage said shoulder and rock said latch member about its pivotal support away from said stop means releasing said latch member and supporting means for retraction movement.

3. A ball-point fountain pen comprising a barrel, a ball point supporting means reciprocably mounted therein and having a ball writing point at its forward end, retracting means for retracting said point into said barrel, a latch member pivotally connected to said point supporting means and rockable between two alternate positions, stop means in said barrel positioned to be engaged by said latch member in one of its said positions, said latch member being free, when in the other of its positions, to reciprocate with said point supporting member, a pushbutton reciprocably mounted within said barrel and carrying a push rod positioned to engage said latch member when said pushbutton is depressed, said latch member having two surface portions engageable respectively by said push rod upon forward move-

ment thereof when said latch member is in either of its two positions to propel said latch member and point-supporting member, whereby upon reciprocation of said pushbutton when said latch is disengaged said rod engages said latch member to move it, together with said point supporting member, forwardly, to engage said stop means at which time said writing point is in and is held in its projected position, and means for returning said pushbutton to a non-depressed position when said stop means is engaged, said push rod being positioned upon the next succeeding depression of said pushbutton to engage and move said latch member to release it from said stop means to effect retraction of said point-supporting member by said retracting means.

4. In a ball-point writing instrument of the type having a barrel, a unit slidable in the barrel including an ink reservoir, a ball-point writing point at the forward end of the unit and adapted to be propelled and retracted through the adjacent end of the barrel, and ink feed means connecting the reservoir and writing point; the combination of spring means constantly urging the unit toward retracted position, a stop element fixed relatively to said barrel, a latch element disposed in driving relation to the unit and movable between latching position with respect to said stop for releasably holding the unit in propelled position when moved thereto and release position wherein the unit is free to retract in the barrel, and a depressible actuating element carried by the barrel reciprocable into engagement with said latch element in either position of the latter, that part of said latch element adapted to be engaged by said actuating element having a pair of laterally spaced abutment surfaces, one of which is engaged by said actuating element to move said unit forwardly into propelled position where it is latched by said latch element and the other is engaged by said actuating element to move said latch element to released position to permit retraction of the unit, and cam means on said latch element between said abutment surfaces for guiding said actuating element into engagement with one or the other of said abutment surfaces dependent upon the position of said unit.

5. In a ball-point writing instrument of the type having a barrel, a unit slidable in the barrel and including an ink reservoir, a ball-point writing point at the forward end of the unit and adapted to be propelled and retracted through the adjacent end of the barrel, and ink feed means connecting the reservoir and writing point; the combination of spring means constantly urging the unit toward retracted position, a stop element fixed relatively to the barrel, a latch element in driving relation with the unit and pivotably movable between a position engaging said stop element and a position disengaged therefrom, and depressible actuating means reciprocable into engagement with said latch element, said latch element having a pair of spaced abutment surfaces adapted to be engaged alternately by said actuating means to move said latch element to its said positions, and cam means on said latch element engaged by said actuating means when it is depressed to guide said actuating element alternately into engagement with said abutment surfaces to propel and latch the unit upon first depression of said actuating means and to unlatch said latch element and permit retraction of the unit upon the next succeeding depression of said actuating means.

6. A propelling and retracting mechanism for a ball-point writing instrument of the type including a barrel, a unit slidable in the barrel and having an ink reservoir, a ball-point writing point at the forward end of the unit and adapted to be propelled and retracted through the adjacent end of the barrel, ink feed means connecting the reservoir and writing point; said mechanism comprising spring means constantly urging the unit toward retracted position, a stop element fixed relatively to the barrel, a latch element carried by the unit and engageable with said stop element when the unit is moved into propelled position, thereby to releasably hold the unit in propelled position, and a depressible actuating element carried by the barrel and adapted to engage said latch element to effect propelling movement of the unit and to enable retracting movement of the unit to be effected by said spring means, said latch element having a pair of laterally spaced abutment surfaces adapted to be engaged alternately by said actuating element when it is depressed, and cam means between said abutment surfaces adapted to be engaged by said actuating element as it is depressed to direct it against one of said abutment surfaces in the retracted position of the unit to propel the unit into latched position and to direct it against the other of said abutment surfaces in the propelled-and-latched position of the unit to unlatch said latch means and permit said spring means to retract the unit.

7. A propelling and retracting mechanism for a ball-point writing instrument of the type having a barrel, a unit slidable in the barrel and including an ink reservoir, a ball-point writing element at the forward end of the unit and adapted to be propelled and retracted through the adjacent end of the barrel, and ink feed means connecting the reservoir and writing element; said mechanism comprising spring means constantly urging the unit toward retracted position, stop means on the barrel, a latch element between the unit and said actuating element and pivotally connected to the unit for rocking movement between a position in line with said stop means and a position displaced therefrom, a depressible actuating element carried by said barrel and positioned to engage said latch element in either of its aforesaid positions for projecting the unit, said latch element having an abutment surface disposed laterally on one side of its pivotal support for engagement with said stop means and a second abutment surface disposed laterally on the other side of said pivotal support, and cam means on said latch element adapted to be disposed in alignment with said actuating element in the latched position of said latch element and adapted to be engaged by said actuating element to guide the latter into engagement with said second abutment surface to rock said latch element away from said stop means as said actuating element is depressed to permit said spring means to retract the unit.

8. A ball-point writing instrument comprising a barrel, a writing unit longitudinally slidable in said barrel and having a writing point adapted to be propelled and retracted through the forward end of said barrel, spring means constantly urging said unit toward retracted position, a depressible actuating element including a flexible actuating rod having a free end extending forwardly toward said writing unit, a forwardly facing stop shoulder in said barrel, a latch element carried by said unit for slidable movement

therewith and for pivotal movement, about a transverse axis, when said latch element is forwardly of said shoulder, between a first position engageable with said shoulder to hold said unit propelled, and a second position slidably rearwardly past said shoulder to permit retraction of said unit, and spring means urging said latch element toward said first position, said latch element having its free end formed with a first cam surface positioned to lie in the path of said actuating element when said latch element is in its first position and to effect pivotal movement of said latch element toward its second position when said actuating element engages and advances said latch element, and a second cam surface positioned to lie in the path of said actuating element when said latch element is in its

second position and to effect pivotal movement of said latch element toward its first position when said actuating element engages and advances said latch element beyond said shoulder.

HERMAN C. FRENTZEL.
